UNITED STATES PATENT OFFICE.

DANIEL COLLINS, OF ZANESFIELD, OHIO.

IMPROVEMENT IN MILLSTONE BALANCES.

Specification forming part of Letters Patent No. 123,678, dated February 13, 1872.

Specification describing a certain Improved Millstone Balance invented by DANIEL COLLINS, of Zanesfield, in the county of Logan, Ohio.

My invention relates to adjustable and variable weights for application to the peripheries of millstone runners, to balance the same on their spindles; and the improvement consists in a peculiar construction of the same, facilitating their application, removal, and variation.

Figure 1 is an elevation of a run of millstones provided with my improved balance. Fig. 2 is a perspective of the balance detached.

In carrying out my invention I employ a box, A, of sheet metal or other suitable material, with an opening, Z, through which to introduce and remove shot or other small weights, the amount of which is thus regulated. To attach this box I employ a plain cylindrical rod, B, with a screw-threaded end y, a pair of matching-dogs, C D, perforated to slip on the ends of this rod, and adapted to engage with the upper and lower edges of the runner-hoop or hoops, as represented in Fig. 1, and a nut, E, and set-screw F, for adjustably holding the said dogs, respectively, the nut E engaging with the screw y, and the set-screw F with a socket in the dog D. The box A is constructed with a sleeve, x, to receive the rod B, and is adapted to occupy the space between it and the stone, when in position, as represented. A slide, G, provided with a set-screw, H, supports the box A at any desired height on the rod B.

To apply the balance, the dog D is set at about the proper point, and secured by the set-screw F, and the nut E turned back until the spurs w of the dogs C and D can be slipped over the edges of the hoops of the runner. The nut is then tightened up, and the spurs w forced in behind the said hoops or bands, when the whole is securely attached. The box A may then be adjusted by means of the slide G and set-screw H, and weights introduced until the stone runs properly.

To remove the balance at any time it is only necessary to turn back the nut E. The rod B being made long enough for the deepest runners, the same balance may be applied with equal facility to any size of stones.

I am aware that variable weights have been used for the purpose contemplated in this invention, and that weights have been attached to the peripheries of millstones by different clamps.

What I claim in this my invention, is—

The improved millstone balance, herein described, composed of the weight-box A constructed with mouth z and sleeve x, the rod B with screw-end y, the adjustable dog D, adjustable support G, loose top-dog C, and clamping nut E, constructed and arranged substantially as shown, for the purpose set forth.

DANIEL COLLINS.
